UNITED STATES PATENT OFFICE.

PARRISH H. RYLANDER, OF AUSTIN, TEXAS.

KNEE PAD.

Application filed December 10, 1921. Serial No. 521,449.

To all whom it may concern:

Be it known that I, PARRISH H. RYLANDER, a citizen of the United States, and resident of Austin, in county of Travis and

5 State of Texas, have invented certain new and useful Improvements in Knee Pads, of which the following is a specification.

This invention relates to knee pads, and the purpose of the same is the provision of 10 a knee pad which is constructed to effect, when in use, the forced ventilation of the padding content as well as the knee of the wearer, whereby the heating of the pad and the scalding of the knee and other parts of 15 the leg is prevented.

It is also a purpose of this invention to provide a knee pad which includes a container constructed to removably receive cushioning material of any character and to 20 hold the material out of direct contact with the knee, and at the same time to provide a resilient seat for the knee.

A further purpose of the invention is the provision of a knee pad having a novel form 25 of attaching means by which the rigidity of the ordinary fastening straps secured to the sides of the usual form of knee pad is eliminated, and the required flexibility provided so that extreme comfort is given to 30 the wearer whether kneeling, standing, bending or walking.

In the accompanying drawings—

Figure 1 is a view showing in applied position one form of knee pad embodying my 35 invention.

Figure 2 is a perspective view of the knee pad shown in Figure 1.

Figure 3 is a transverse sectional view of the knee pad shown in the preceding views.

40 Figure 4 is a perspective view of the knee pad shown in Figure 1 and with the cushioning material and attaching straps removed.

Figure 5 is a perspective of a modified form of the invention.

45 Figure 6 is a perspective of the improved knee pad open, the filling being omitted.

Similar reference characters refer to similar parts in each of the several views.

Referring specifically to the drawings, the 50 invention in its present embodiment comprises a container designated at "K" and formed of resilient material such as leather, vulcanized canvas, rubber or the like. The container "K" includes a body portion 15 55 integrally formed at its longitudinal edges with side portions 16 which are bent to over-

lie the body portion and having their free longitudinal edges spaced apart to provide an air-gap 17 that is co-extensive in length with the body portion.

60 The side portions are secured together at one end by means of a fastening member 18 so as to permanently provide the gap 17 and to maintain the side portions in overlying relation with respect to the body portion 15. 65 By this arrangement, a compartment is formed between the side portions and body portions, and this compartment is adapted to receive a cushioning material such as cotton, hair or the like as indicated at 18^a in 70 Figure 3.

At the upper or left hand end of the body portion 15 is provided a hood 19 adapted to embrace the leg at a point above the knee as clearly shown in Figure 1. This hood 19 is 75 a continuation of the material comprising the body portion 15, and is formed by bending the hood at right angles to the body portion and securing its vertical edges to the sides of the container by means of rivets 80 20 or other fastening means. In this manner the hood assumes a curved form and is held in right angular position with respect to the container so that it will properly embrace the leg when the pad is in applied 85 position.

At the opposite end of the body portion 15 and within the pad receiving compartment a flap 21 is secured by means of rivets 22. This flap is bent so that it overlies the side 90 portions 16 and thus spans the gap 17, and partially closes the lower end of the compartment, thus providing means for retaining the cushioning material 18^a against displacement from the compartment. As 95 shown, the flap 21 is perforated for the purpose of permitting the circulation of air into and through the compartment as will be more fully described hereinafter. For attaching the pad as a unit to the leg of the 100 wearer, two straps S and S' are provided. As shown in Figures 1 and 2 the strap S is trained through incisions 23 of the hood 19 and is secured to the free end of the flap 21 by a rivet 24. By this arrangement it will 105 be seen that the strap S serves to maintain the flap 21 in covering position with respect to the container so as to prevent displacement of the cushioning material. The strap S' is trained through incisions 25 of the side 110 portions 16, and it is secured to the body portion 15 by means of the rivets 22 em-

ployed for securing the flap 21 to the body portion as is clearly shown in Figure 3.

In practice, the pad is attached to the leg in the manner shown in Figure 1 with the straps S and S' trained about the leg at points above and below the knee. By virtue of the manner in which they are attached the straps are practically continuous and function in a manner similar to a belt, thereby providing an extremely comfortable attaching means. As the container "K" is formed of resilient material, it will be clear that because of the arrangement of the side portion 16 with respect to the body portion 15, the container is resilient, that is, after having been compressed under the weight of the leg, it automatically expands to normal position. This expansive movement is enhanced by the cushioning material 18 within the compartment. By virtue of this resilient container it is caused to occupy expanded and contracted positions during the normal use of the pad. For example, in the normal position of the pad, the container, is expanded, but when the wearer is kneeling on the pad it is compressed.

When the wearer rises and the pad is relieved of the pressure, it expands, thus causing the air to circulate into the pad receiving compartment. The air gap 17 and openings at the opposite ends of the container, provide avenues through which the air is permitted to circulate, while at the same time air is caused to circulate about the knee of the wearer through the perforations of the flap 21, every time the knee is put down and raised up. This method of ventilation obviously prevents heating of the cushioning material and scalding of the knee, so that a comfortable knee pad is at all times assured.

It is to be particularly noted that the cushioning material 18^a is removable from the container. This permits of the substitution of new material when the old becomes packed and hard, and it is of special advantage to cotton pickers as the cotton can be used for the cushioning material and the picker can readily substitute new cotton while working in the field.

In view of the foregoing, it is thought that the operation of the device will be readily apparent and in view of the simplicity and practical value that it will readily commend itself to those skilled in the art.

As illustrated in Figures 5 and 6, the improved knee pad may be formed from a single blank of yieldable material designated by the numeral 30 and which is provided with oppositely arranged transverse incisions 31 intermediate its ends, which define intermediate wings 32 and end wings 33, the end wings 33 being adapted to overlap the intermediate wings 32 so that rivets 34 may be extended through the aligned apertures 35 and 36. When the wings 32 and 33 have

thus been connected, the portion of the body between the incisions 31 is partly folded or turned so as to provide an end wall 37 which joins the side walls formed by the wings 32 and 33. The side walls formed by the wings 32 and 33 and the end wall 37 formed between the wings 33 defines a pocket for the reception of a filling element or cushioning member carried by a filler to be described.

At one end of the body 30 the same is provided with an extension 40 having laterally extending sides 41 between which a cushioning element is adapted to be arranged. When the cushioning element has been arranged upon the extension 40 and between the sides 41 said sides may be connected by means of fastening devices 42 of any suitable character. The fastening devices 42 are extended through openings in the edge portions of the sides 41 and maintain the longitudinal edges of the sides 41 in spaced parallel relation, thereby providing a means to permit the passage of air through the cushioning element. When the cushioning element has thus been secured within the holder for the same, the holder is folded into the pocket formed by the wings 32 and 33 and the end walls 37 and the holder for the cushioning element is held within the pocket by means of an attaching strap 40 passed through longitudinally extending incisions 45 in the extension 40.

The strap 44 is also extended through the diagonally extending incisions 47 in the terminal portion of the wings 33. One end portion of the strap 44 is provided with a buckle 48 through which the free end portion of the strap is extended when the improved pad is applied to one's knee.

The lower portion of the pad is held in position by means of a strap 49 passed through longitudinally extending incisions 50 in the side wings 32.

It is thus seen that the attaching strap 44 not only serves as a means for securing the pad to one's knee but also as a means for securing the cushion holder within the pocket provided by the several wings in the end wall 37. In order that the pad might be thoroughly ventilated the extension 40 is provided with a series of apertures 56 through which the air may pass.

What is claimed is:—

1. A knee pad comprising a container formed of resilient material arranged to provide a resilient seat and having openings therein to allow the passage of air interiorly of the container between the latter and the knee when in applied position, a pad housed within the container, and attaching means for the container.

2. A knee pad comprising a container formed of resilient material arranged to provide a resilient seat capable of occupying expanded and contracted positions, a

pad within the container, a flap covering secured to the container and having openings formed therein through which air is adapted to be forced interiorly of the container under the movement of the latter to effect cooling of the pad and to prevent scalding of the knee.

3. A knee pad comprising a container formed of resilient material and including 10 a body portion and side portions bent to overlie the body portion to provide a cushion receiving compartment, a flap covering secured to the body portion and overlying the side portions, a portion formed integral 15 with the body portion, said flap covering being perforated and associated with the body and side portions to allow the passage of air into and out of said compartment, and attaching means carried by the 20 hood and body portions.

4. A knee pad comprising a container formed of resilient material and including a body portion and side portions bent to overlie the body portion to provide a cushion 25 receiving compartment, a flap covering secured to the body portion and overlying the side portions, a portion formed integral with the body portion, said flap covering being perforated and associated with the 30 body and side portions to allow the passage of air into and out of said compartment, said hood and body portions being slitted, and straps extended through said 35 split portions and fixedly secured to the container.

5. A knee pad comprising a container formed of resilient material and including a body portion having side portions bent to overlie the body portions and secured 40 at the confronting edges to provide a pad receiving compartment, a pad within the compartment, a hood on one end of the body portion, a flap covering secured to the body portion and overlying the latter, said 45 flap covering being perforated and associated with the side portions to allow the circulation of air into and out of the said compartment, and attaching straps extending through the hood portion and body portion 50 and secured to the body portion and to said flap covering.

6. A knee pad formed from a single length of elongated material having incisions defining intermediate and end wings, the said wings having their adjacent portions overlapped and connected to define a pocket, a cushioning member received in 55 said pocket and an attaching strap extending through certain of said wings, said attaching strap forming a means whereby the pad may be secured to the knee.

7. A knee pad formed from a single length of elongated material having incisions defining intermediate and end wings, having their adjacent portions overlapped 65 and connected whereby to define a pocket, cushioning means received in said pocket, and an attaching strap extending through certain of said wings, said length of material having one end provided with an integral carrier for said cushioning member.

8. A knee pad formed from a single length of material having oppositely arranged transverse incisions defining intermediate and end wings, the said wings having 75 their adjacent portions connected to define a pocket, one end portion of said pocket being provided with a longitudinal extension having sides, a cushioning element mounted on said extension and confined between said sides, and fastening devices extended through said sides whereby to hold the cushioning element in position.

9. A knee pad formed from a single length of material having oppositely arranged transverse incisions defining intermediate and end wings, the said wings having their adjacent portions connected to define a pocket, one end portion of said 85 pocket being provided with a longitudinal extension having sides, a cushioning element mounted on said extension and confined between said sides, fastening devices extended through said sides whereby to hold the cushioning element in position, and an 90 attaching strap extending through said extension and certain of said wings whereby to hold the cushioning element in position and to form a means whereby the pad is secured to one's knee.

PARRISH H. RYLANDER.
